UNITED STATES PATENT OFFICE.

JOHN G. BAUER, OF WARSAW, NEW YORK.

FOLDING SUIT-BOX.

1,122,464.

Specification of Letters Patent. Patented Dec. 29, 1914.

Application filed July 2, 1913. Serial No. 777,045.

To all whom it may concern:

Be it known that I, JOHN G. BAUER, a citizen of the United States, residing at Warsaw, in the county of Wyoming and State of New York, have invented certain new and useful Improvements in Folding Suit-Boxes, of which the following is a specification, reference being had therein to the accompanying drawing.

10 This invention relates to folding boxes and has for its object the production of a simple and efficient box wherein the same may be folded so as to constitute a reinforcement for the folded end thereof.

15 Another object of this invention is the production of a simple and efficient means for bracing the inner ends of the side flaps of the box so as to constitute a rigid partition at each end or side of the box.

20 With these and other objects in view, this invention consists of certain novel constructions, combinations and arrangements of parts, as will be hereinafter fully described and claimed.

25 In the drawings:—Figure 1 is a perspective view of the box partly open. Fig. 2 is a horizontal section through one of the rear corners of the box showing the reinforcing means therefor. Fig. 3 is a vertical transverse section through the reinforcing means at the rear ends of the side or end flaps of the box. Fig. 4 is a blank view of the box prior to the folding of the same. Fig. 5 is a detail perspective of one corner 30 of the box showing a modified form of securing the corners together. Fig. 6 is a detail perspective of a modified form or manner of attaching the reinforcing flap to the rear of the box.

40 By referring to the drawings, it will be seen that 1 designates the bottom of the box which carries at its rear end a folding wall 2. A top or cover 3 is connected to the folding wall 2 as is clearly illustrated in Figs. 1 and 4 and this folding wall 2 is provided at each end with a folding reinforcing flap 4.

The bottom portion of the box comprises a body portion having end flaps 5 and a front flap 6. The front flap 6 is provided 50 with notched portions 7 into which the locking flaps 8 fit for holding the end flaps 5 and front flap 6 in their correct position relative to the base of the bottom 1, or, in other words, at right angles thereto. The 55 top section 3 is formed in like manner to that of the bottom section 1 and comprises

the end flaps 9 and a front flap 10, the front flap 10 being provided with the notches 11 for receiving the locking lips or flaps 12 of the end flaps 9. The folding reinforcing flaps 4 which are placed upon opposite sides of the box are formed by cutting the strip which constitutes the end flaps 5 and 9 on the lines indicated by the numeral 13 in Fig. 4. It will, therefore, be seen that this reinforcing flap will not necessitate the employing of additional material as the entire device may be formed of a substantially square sheet and the end flaps may be so formed by merely cutting the side portion 70 of the blank on the lines indicated by the numeral 13, thereby producing the folding reinforcing flap 4.

As is clearly illustrated in Fig. 1, the folding reinforcing flaps 4 are interposed between the end flaps 5 and 9 of the box, and this folding reinforcing flap 4 resists the lateral movement of these flaps 5 and 9 and it will, therefore, be seen that this reinforcing flap 4 will be held out of engagement with 75 foreign objects in view of the fact that this folding reinforcing flap 4 is shielded between the end flaps 5 and 9 of the box. This folding reinforcing flap 4 by being formed integral with the rear partition or wall 2 80 will not be likely to become torn or disengaged from the box. By carefully considering Fig. 2, the manner of placing the folding reinforcing flap 4 between the flaps 5 and 9 of the bottom and top of the box will 85 be clearly seen.

In using folding boxes of the nature just described, it should be understood that there is a great tendency for the box to tear at the place of folding and especially at the point 90 of connection of the end flaps with the body at the point of folding which would tend to rip the side flaps 9 and 10 longitudinally from the body of the box if this reinforcing portion were not placed in the position as 100 illustrated in Fig. 1. By having this reinforcing portion so placed, as illustrated in Fig. 1, it will be seen that the outward bulging of the side portions due to the pressure of the goods within the box will be resisted.

It, of course, should be understood that in place of the corner connection illustrated in Fig. 1 by the numerals 11 and 12 the corners of the box may be secured by means of an adhesive strip as per Fig. 5 of the drawing.

In Fig. 6 of the drawing I have shown

an embodiment wherein the reinforcing flap 4' is formed integral with one of the side partitions 5' and this flap is adapted to be folded inwardly and lie snugly against the back portion 2' when the box is in the folded position.

Having thus described the invention, what is claimed as new, is:—

10 A folding box formed from a blank sheet of material and comprising a primary and an auxiliary section, said sections being connected by an intermediate portion, said primary and auxiliary sections provided with side flanges, said intermediate portion provided with projecting tongues adapted to fit

between the flange portions of said primary and auxiliary sections of said box, and being free to move away from said flange portions of said sections of said box as said box is opened, and said tongues constituting reinforcing means for bracing said sections of said box when the same is in a folded position. 20

In testimony whereof I hereunto affix my signature in presence of two witnesses.

JOHN G. BAUER.
